H. G. LAMBERT

GASOLINE FILTER ATTACHMENT FOR MOTOR VEHICLES

Filed Sept. 9, 1924

H. G. Lambert Inventor

By Warren O'Brien
atty.

UNITED STATES PATENT OFFICE.

HENRY G. LAMBERT, OF ROFF, OKLAHOMA.

GASOLINE-FILTER ATTACHMENT FOR MOTOR VEHICLES.

Application filed September 9, 1924. Serial No. 736,759.

To all whom it may concern:

Be it known that I, HENRY G. LAMBERT, a citizen of the United States, residing at Roff, in the county of Pontotoc and State of Oklahoma, have invented certain new and useful Improvements in a Gasoline-Filter Attachment for Motor Vehicles, of which the following is a specification.

This invention relates to improvements in gasoline filter attachments for motor vehicles and has for its primary object to provide a simple and efficient device which is placed in the feed line between the vacuum tank and the pipe leading to the carburetor for the purpose of filtering the gasoline before the same is delivered to the carburetor.

Another important object of the invention is to provide a gasoline filter attachment of the above mentioned character, wherein the same is of such a construction as to enable the parts to be readily disassembled for the purpose of removing the filter and cleaning the same.

A further object of the invention is to provide a gasoline filter attachment of the above mentioned character, which at all times will be positive and efficient in its operation and will not in any way interfere with the operation of the motor vehicle or the feeding of the gasoline from the vacuum tank to the carburetor.

A still further object is to provide a gasoline filter attachment of the above mentioned character, which includes a means for cutting off the gasoline supply to the carburetor when the filtering member has been removed for cleaning purposes.

A still further object is to provide a gasoline filter attachments of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a side elevation of my improved invention showing the same in position with respect to the vacuum tank and the feed pipe, and

Figure 2 is a vertical sectional view of the attachment.

In the drawing wherein for the purpose of illustration is shown the preferred embodiment of my invention, the numeral 1 designates the body of the filter attachment, and the same is provided at its upper end with the reduced threaded portion 2 for attaching the body member to the vacuum tank A. The portion between the reduced threaded portion 2 and the main body portion 1 is substantially square as illustrated at 3 for the purpose of providing a means whereby the tool may be used in attaching the body member to the bottom of the vacuum tank.

The body member is provided with a longitudinally extending bore 4, the lower portion of the body member 1 is provided with an enlarged recess 5 and the purpose thereof will be presently described. The enlarged recess 5 is adapted to communicate with the bore 4 of the body member 1 as is clearly illustrated in Figure 2. Threaded into the lower portion of the recess 5 is the plug 6. The lower end of the plug is reduced and externally threaded as illustrated at 7 and is adapted to be connected to the feed pipe B, the portion above the reduced threaded portion being substantially square as illustrated at 8 to facilitate the attaching of the plug to the feed pipe. The plug 6 is also provided with a longitudinal bore 9 and the same communicates with the bore 4 formed in the body 1 in the manner as illustrated more clearly in Figure 2.

The upper portion of the plug 6 is spaced from the inner wall 10 of the enlarged recess 5 and adapted to be removably supported therebetween is the filter designated generally by the numeral 11. In this manner the filter may be removably supported within the enlarged recess 5 and between the communicating bores 4 and 9 respectively so as to cause the gasoline passing from the vacuum tank through the body and the plug to be filtered before entering the feed pipe B and being delivered to the carburetor (not shown). The sediment will be collected by the filter and the filter may be easily and readily removed from the enlarged recess by removing the plug 6 whereby the filter may be cleaned or replaced.

For the purpose of cutting off the supply of fuel from the vacuum tank to the feed

pipe when the parts of the attachment are disassembled particularly when the filter is being cleaned, I provided the body with a transversely extending tapered bore 12 through which extends a rotary valve 13, the same having the opening 14 thereof adapted for communication with the bore 4 of the body 1 when in its normal position. A handle 15 is formed on the enlarged outer end of the valve for facilitating the operation thereof and a coil spring 16 is associated with the smaller end and the adjacent portion of the body for normally holding the valve in an open position.

15 The provision of an attachment of the above mentioned character, in the gasoline feed line between the vacuum tank and the carburetor will insure the supply of gasoline to the carburetor in a clean state free from dirt and other foreign substances, thereby increasing the efficiency in the operation of the engine. Furthermore, the provision of gasoline filter attachment of the above mentioned character, enables the same to be readily and easily disassembled without the loss of any considerable length of time and labor.

20 While I have shown the preferred embodiment of my invention, it is to be understood that various changes in the size, shape

and arrangement of parts may be resorted to without departing from the spirit of the invention and the scope of the appended claim.

Having thus described the invention, what I claim is:—

In combination with the fuel feeding means of a motor vehicle including a vacuum tank and feed pipe, of a filter attachment associated therewith, comprising: a body member, the upper end thereof being threaded into the vacuum tank, said body member having a longitudinal bore, the lower portion of the body having an enlarged recess therein communicating with the bore, a plug threaded into the lower portion of the recess, the lower end of the plug being connected to the feed pipe, said plug having the longitudinal bore therein communicating with the aforementioned bore, a filter element removably supported in said enlarged recess between the inner wall thereof and the upper face of the plug, means for cutting off the supply of fuel from the tank to the feed pipe, said means comprising a rotary valve mounted transversely in the body above said recess.

In testimony whereof I affix my signature.

H. G. LAMBERT.
